UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

PENCIL.

Application filed January 5, 1922. Serial No. 527,086.

My invention relates to pencils. It has special reference to mechanical pencils wherein actuating devices are provided for propelling a lead through the body of the pencil into exposed position.

This invention has special reference to improvements in my pending application, Serial No. 500,555, now Patent No. 1,490,247, wherein substantially the same form, substance and arrangement of parts are present.

This invention has special reference to parts functioning to advance the lead that embrace characteristics of structure that will permit a retraction of the feeding mechanism without the requirement of turning the same in screw action manner.

In the drawings Fig. 1 is a side elevation showing the pencil with parts in complete assembly.

Figure 2 is a vertical sectional view longitudinally through the center of the pencil.

Figure 3 is a cross sectional view on the line 3—3 of Figure 2.

Figure 4 is a cross sectional view on the line 4—4 of Figure 2.

Figure 5 is a detailed view of a shell adapted for relation to the general structure to effect a normal closure of an extra lead container space.

Figure 6 is a view at right angles of Figure 5.

Figure 7 is a cross sectional view on the line 7—7 of Figure 2.

Figure 8 is a cross sectional view on the line 8—8 of Figure 2.

The pencil herein exemplified has as its general object, (as is particularly pointed out in my co-pending application 500,555,) the provision of a pencil that is readily separable as to parts so that it may be taken down by the user to the end of correction of faults or defects that may develop in its use. Also in this, and in the application referred to, I have applied the lead propeller to its operative support in a manner to carry out its general purpose of advancement to propel the lead wherein a screw action movement is essential. I have herein provided such relationing of the lead propeller to its support that the latter may be moved rearwardly by direct pull to effect release of the propeller from the feed member without the requirement of the turning action of its support that attended its advancement.

In the companion application referred to, the threaded lead propeller, it will be noted, co-operates with a fixed threaded feed member within the shell whereby through advancement within and beyond the fixed threaded member, it may be brought in contact with the lead. The same principle is involved here, but I have advanced the thought a step farther with the idea of eliminating the requirement of applied screw action to the lead propeller to cause its release from the fixed threaded member. This object is attained by mere exaggeration over the ordinary degree of screw pitch, both as to the lead propeller and the fixed threaded member, and providing sufficient clearance that in the co-action of the propeller and the threaded member, the former, acting under a direct pull, may readily be withdrawn from the fixed threaded member. It is to the detailed means and the general thought herein set out that my present invention is directed.

Referring to the drawings, 10 is a main casing or body terminating at its forward end with a gradually tapered portion 11. 11^a is a tip which I shall not refer to specially as it forms no part of the present invention. 12 is a feed or union member provided with a centrally disposed threaded way 13. A forwardly extending part 14 of the union member is of larger diameter threaded bore than that of the threaded opening 13 in the main body of the union member. A rearwardly extending part 16 of the union member is formed at its rear extremity with a tapered centering way 17. 18 is a flanged shell fixed in the tube against which the feed or union member 12 is adapted to abut. 19 is a lead guide fashioned for union respectively at one end with the feed or union member and at the other end with the tip, and being fashioned with an inward taper at its rear end as at 20 to facilitate centering with respect to a lead propeller and the bore of the lead guide. 21 is a tube or interior casing comprising members 22 and 23 suitably joined, its forward end being fixed to the feed or union member and its rear end abutting with casing 10, through its flange member 23^a. The flange portion 23^a of the tube is provided with clearance ways or openings 24 (see Fig. 3) to facilitate entry of extra leads. 25 is a

flanged spacing ring fixed to tube 21 which also serves to define the forward limits of an extra lead chamber. 26 is a shell or actuating member provided with longitudinal channel ways 27, and is threaded as at 28 to facilitate union with a threaded extension 29 of a closure member 30 of a head member hereinafter particularly referred to. The forward end of the tube 26 is fashioned as 10 at 31 to provide a clearance seat for a cross head 34 of the lead propeller, later to be described, said shell being inturned as at 32 to form a thrust bearing to limit forward advancement of the lead propeller and is 15 fashioned with respect to the cross head of the lead propeller to facilitate the latter's turning within the clearance space 31 of the tube with the least possible friction.

33 is a lead propeller, the same being 20 threaded throughout the greater portion of its length at a pitch in exaggeration of normal screw threads to conform with a similar exaggeration in screw pitch of the threads in the feed or union member. The 25 lead propeller is supported within and related to the shell member 21 in a manner to permit relative longitudinal movement therebetween without excessive friction. The lead propeller is provided with a laterally extending portion or cross head (which in the exemplification herein consists in merely flattening the body of the propeller as at 34) adapted to engage the channel ways 27 in shell 26 whereby the lead propeller is permitted to reciprocate within the tube but is related thereto in a manner that it is turned with the tube. In practice the lead propeller, having been advanced, with its forward end lodged in the centering way 40 17 of feed or union member 12, by turning the tube 21, its threaded portion will be caused to engage the threaded portion of the feed or union member and thereby will be advanced into position to apply pressure 45 to the lead section within the lead guide.

Attention is here specially called to the functioning of the lead propeller with respect to the feed or union member in the matter of the former being withdrawn from 50 the latter under direct pull and without the necessity of manual application to promote screw action. The action is as follows:

The lead propeller having been advanced within the shell 26, into a position where 55 the latterly projecting members thereon are in relief of the channel ways 27 and lodged within the clearance space 31, then, because of the exaggerated pitch of the threads of the propeller and feed or union member and 60 the thrust bearing 32 and because, in the position described, the propeller is in relief of the lateral stop effected by the channel ways in the tube, by direct pull applied to said shell it will be withdrawn from tube 65 21 and similarly the lead propeller will be

withdrawn. The action of such line pull will cause the propeller to be turned within the feed or union member until in complete relief of the latter and this without applying any screw action to shell 26; the action 70 being that as in the so-called "Yankee" screw driver.

35 is a shell member adapted to be seated between the outer wall of the tube 21 and the inner wall of the portion 26 of tube 21 75 and is so related to the rearward end opening of the extra lead space within the casing as to effect normal closure against exit of lead sections, but co-operating in conjunction with shell 26 to effect such closure and so opening as is desirable in carrying out the purposes and uses of the pencil, all of which is fully described in my pending application, Serial No. 500,555.

A head section is essential to the carrying 85 out of the purpose of the pencil herein exemplified, which I refer to generally as 36 but will make no special reference thereto as it is not a part of my present invention and furthermore is shown in detail substantially as here in my aforesaid co-pending application. The member herein referred to as 30, which is connected to casing 26, is a part of head member 36 and is connected therewith in a positive manner, and beyond this noted fact there is no requirement for special reference to said head member except to say that it is the means applied to the tube for the convenience of the latter's manipulation and serves in a general way as 90 a closure to the rear end of the casing.

What I claim is:

1. In a pencil, a casing, means within the casing for guiding a lead, screw acting means within the pencil for advancing the 105 lead comprising a threaded feed member fixed within the casing, a threaded lead propeller co-operating therewith, the threads of said co-operating members having a steep pitch, and an operating member fashioned 110 for guiding the lead propeller and operative to turn the latter and to permit relative longitudinal movement therebetween, but provided with clearance space and a thrust bearing at its forward portion, whereby, 115 upon direct pull upon the operative member the propeller is caused to turn freely therein under the pull of the feed member.

2. In a pencil, a casing, means within the casing for guiding a lead, threaded means for advancing the lead, comprising a stationary internally threaded part and a projectable member, an operating element for guiding said member, fashioned to permit relative reciprocation therebetween, the combined turning action of said element and member causing the advancement of said member within the pencil, said element being provided with clearance space and a thrust bearing at its forward end whereby 130

in a certain relative longitudinal position only of said member and said element the said member will be free to rotate relatively to said element.

- 5 3. In a mechanical pencil, a casing, a threaded propeller, a threaded screw feed member in threaded engagement with said propeller, means for causing relative rotation of said last two mentioned parts to project a lead from said casing, and said first mentioned means being provided with a thrust bearing and clearance space for releasing said propeller from said first mentioned means, the threads on said propeller 10 and feed member having an exaggerated pitch for causing an unscrewing movement between said threaded members upon a straight longitudinal pull on one of them to retract the propeller when the propeller has 15 substantially reached its forwardmost position.

4. In a mechanical pencil, a casing, a threaded feed member fixed within the casing, a propeller for ejecting lead from said casing, threads associated with said propeller for engagement with the threads of said feed member to cause longitudinal movement of the propeller upon relative rotation of the threaded parts, a rotatable actuating member, said propeller having connection with said actuating member to rotate therewith and be longitudinally slidable with relation thereto, said actuating member being provided with a clearance space and thrust bearing for releasing said propeller from said actuating member, the threads on said propeller and feed member having an exaggerated pitch for permitting the withdrawal of said propeller rearwardly by a straight longitudinal pull on said actuating member, said withdrawal being possible when said propeller is in substantially its most advanced position with relation to said actuating member.

- 45 5. In a pencil, a casing having a threaded feed member fixed thereto, an interior actuator shell rotatable with relation to the feed member and having a longitudinal guideway therein and a thrust bearing at the end thereof, a propeller having threaded engagement with said feed member and a projection for longitudinal sliding engagement with said guideway as the propeller is rotated with the shell, said guideway terminating short of the inner end of the shell to form a clearance space in which said projection may rotate with relation to the shell to permit with-

drawal of the propeller by straight longitudinal pull on said shell.

6. In a pencil, a casing, lead propelling mechanism comprising inner engaging threaded parts including a lead propeller, an actuator for rotating one of said parts with relation to the other, and means to effect an unscrewing movement of said inner engaging parts and to effect the retracting upon a straight longitudinal pull of said actuator.

7. In a mechanical pencil, a casing, an internally threaded member fixed within said casing, a threaded propeller adapted for threaded engagement with said internally threaded member, means for actuating said propeller with relation to said casing, the threads on said propeller and in said internally threaded member being of steep pitch, said actuating means being provided with a clearance space for releasing said propeller from said actuating means whereby when the propeller has reached its position of maximum projection a straight longitudinal pull on said actuating means will cause the propeller to be actuated and retracted.

8. In a pencil, a casing, lead propelling mechanism, comprising inter-engaging threaded parts including a lead propeller, an actuator for rotating said propeller with relation to the other part, said actuating member being provided with a clearance space and a thrust bearing for releasing the propeller from said actuator, said threaded parts having threads of exaggerated pitch to effect an unthreading movement of said inter-engaging parts and to effect the retracting upon a straight longitudinal pull of said actuator.

9. In a pencil, a casing, lead propelling mechanism comprising inter-engaging threaded parts including a lead propeller provided with a projection, an actuator for rotating one of said parts in relation to the other and comprising a shell provided with a thrust bearing at the end thereof and a guideway adapted for engagement with said projection and terminating short of the end of said shell providing a clearance space in which said projection may rotate with relation to the shell to permit withdrawal of the propeller by a straight longitudinal pull on said shell.

In testimony whereof I affix my signature.

JOHN C. WAHL.
